UNITED STATES PATENT OFFICE.

WILLSE LAWRENCE, OF SPRINGFIELD, MASSACHUSETTS, ASSIGNOR TO UNITED STATES MANUFACTURING COMPANY, OF SOUTH DEERFIELD, MASSACHUSETTS, A CORPORATION OF MASSACHUSETTS.

MEANS FOR MOUNTING MACHINE-GUNS.

1,322,457.

Specification of Letters Patent. Patented Nov. 18, 1919.

Application filed May 2, 1917, Serial No. 166,012. Renewed August 23, 1919. Serial No. 319,428.

To all whom it may concern:

Be it known that I, WILLSE LAWRENCE, a citizen of the United States, residing at Springfield, in the county of Hampden and 5 State of Massachusetts, have invented new and useful Improvements in Means for Mounting Machine-Guns, of which the following is a specification.

This invention relates to means for 10 mounting machine guns of the type employed in trench warfare, and one object is to provide improved means for turning the gun in a horizontal direction on a stationary base, in order that the gun may be 15 aimed in any direction, and a further object is to provide for the elevation of the muzzle of the gun, or of the breech thereof, in order to produce any desired inclination between the horizontal and the vertical, and 20 in order to produce the downward inclination of the muzzle when desired.

A further object is to provide means whereby the devices controlling the inclination or angle of the gun may be so operated 25 that the change of inclination may be effected gradually, or may be effected immediately and in one operation when the gun is to be moved through a considerable angle at a given time. A micrometer adjustment is provided for securing gradual 30 and accurate movement of the gun with reference to the supporting device.

A further object is to provide means suitable for mounting any one of the machine 35 guns now in use by the U. S. Army, these guns including the Lewis gun, the Maxim gun, the Maxim-Vickers gun, the Colt gun and the so-called U. S. B. M. gun. The only change necessary in mounting any of 40 the guns indicated is in applying suitable attaching or securing devices for holding the gun in position upon the gun base of the standard type which I am now constructing.

45 With the foregoing and other objects in view, the invention consists in the novel construction, combination and arrangement of elements hereinafter described and claimed:—

50 In the accompanying drawings:—

Figure 1 is a view of the device in side elevation.

Fig. 2 shows the general construction in front elevation.

Fig. 3 is a top plan view. 55

Fig. 4 is a section on the line 4—4 of Fig. 3.

Fig. 5 is taken on the line 5—5 of Fig. 1.

Fig. 6 is a detail view in perspective of a bracket located between the gun base 60 proper and certain of the vertical supports.

Fig. 7 is a section on line 7—7 of Fig. 4.

Figs. 8 to 11 are details showing certain 65 securing devices by means of which the guns of various types in use by the U. S. Army may be connected with the gun base.

Fig. 12 is a section on line 12—12 of Fig. 1.

Fig. 13 is taken on line 13—13 of Fig. 5.

In my application for patent filed April 70 12, 1916, Serial No. 90,689, I have described means for mounting a machine gun designed to permit of the manipulation of a gun from a point below the gun base, in order that the weapon may be mounted in a 75 trench or the like. In the present application I provide means for manipulating the gun in all directions necessary, permitting it to be rotated entirely around the lower portion or stationary base, and permitting 80 any elevation of the muzzle and conversely any reasonable elevation of the breech portion when the muzzle is to be pointed in a downward direction. Vertical adjustment of the gun base is secured through means 85 similar to those described in my pending application.

The stationary base includes an annular member 10 supported by suitable legs constituting a tripod, this base serving to carry 90 a turn-table 15 and having on its outer edge teeth 16 adapted to coöperate with a worm 17 in order to provide for the very accurate adjustment of the turn-table with reference to the base. Worm 17 is mounted on a shaft 95 18 adapted to be operated by a hand wheel 19, said shaft 18 being supported by a bracket 20 pivoted at 21 and adapted to be swung into and out of engagement with the teeth above mentioned. The position of 100 the bracket is controlled by set screw 22 engaging pin 23, pivoted at 24.

Mounted transversely of the base and turn-table is an angle bar 25 and positioned at points adjacent to the ends of said bar 105 26 are upwardly extending members or lugs 26 apertured and adapted for the accommodation of pins 27 constituting trunnions for

supporting the vertical members or uprights 28 and 29 which support the gun base 30 at the elevation desired. Members 28 and 29 comprise angle bars positioned as indicated, and connected with the tops of these bars by means of pivots 31 are a plurality of arms 32 deflected at portions 33 and threaded for a considerable distance adjacent to their lower ends. The threaded portions pass through sleeves 35 provided with beveled gears 36 engaging beveled pinions 37 carried by a shaft 38 extending transversely and provided in turn with a beveled pinion 39 engaging beveled gear 40. The gear wheel last-named is carried by the short shaft 41 operated by means of hand wheel 42, said shaft having a bearing 43 in an arm 45 extending rearwardly from the rotatable member carried by the base. This construction provides for the tilting of the vertical members 28 and 29 and consequently for the elevation of the breech or muzzle when aiming the gun in a desired direction. Said members 28 and 29 are connected at their lower ends with angular members 28' and 29' on which the trunnions are directly mounted.

The gun base includes a member having a substantially plane upper surface and designated 30, this member having downwardly extending flanged portions at each side, shown at 49, and reinforcing ribs or the like 50 and 51. Flanged members 49 are provided with slots 52 permitting of the adjustment of the gun base in a vertical plane by means of threaded member 54 constituting a handle and having threaded connection with the flanged portions of a bracket 55 mounted between the uprights 28 and 29. The bracket last referred to is shown in detail in Fig. 6 and comprises side members 59 and 60 spaced apart and connected at their front ends by a transverse member 61. The vertically disposed flange portions 49 of the gun base are positioned between the side members of the bracket mentioned and a pin 62 passes transversely through the bracket and through members 49 of the base for the purpose of pivoting the latter to the bracket.

One side of the bracket is provided with an offset member 64 having an apertured socket member 65 mounted thereon, said socket member receiving the threads of a screw 66 extending parallelly with reference to the vertical bars 28 and 29 and controlled by means of gear 67 at the lower end, said gear meshing with a beveled pinion 68 adapted to be operated by means of a handle constituting a crank arm 69. This construction provides for the movement of the gun base vertically within the supporting frame comprising members 28 and 29. The screw 66 is supported at its upper end in a bracket or the like 71.

In order to provide for guiding the gun base in its vertical movement I provide a plurality of guiding plates 72 and 73 on which are mounted a plurality of rollers 74 adapted to engage respectively opposite sides of certain of the flanges of angle bars 28 and 29, this construction being shown in detail in Fig. 3 and also being partially shown in Fig. 4. One of these plates is carried on outwardly extending member 64 and at an angle of approximately 45 degrees with the longitudinal axis of the gun base, and the other of said plates is carried upon a correspondingly formed member 76 on the opposite side of the bracket. Member 64 is provided with a latch or the like 78 pivoted at 79 and having an edge 80 adapted to coöperate with the threads of screw 66, said latch being retained in position by means of a detachable pin or the like 81 and being thrown into disengaging position by means of a projecting member 82. The latch is in engagement with the threads of the screw during the gradual elevation or the gradual downward movement of the gun base, but when a more rapid movement or adjustment is desired the latch may be thrown out of engagement with the screw.

A similar gradual adjustment is effected by the operation of member 19 controlling the rotation of the turn-table, this being in fact a micrometer adjustment, but when it is desired to turn the gun through a considerable angle the bracket supporting the worm is swung outwardly in order that said worm may be disengaged from the teeth, as already indicated. It should be added that the rotary member is held in proper position with reference to the stationary portion by means of rollers 8 carried by downwardly extending members or arms 9 secured to said rotary member.

A reel 84 is mounted on arm 85 extending at an angle with a plate member 86 secured by means of thumb screws 87 to angle bar 29. This reel may therefore be detached when desired.

The front portion of the gun base 30 is provided with an aperture 88 which may be engaged by certain of the securing devices carried by given types of guns. This gun base is also provided with apertures 90 designed for similar purposes. In Figs. 8 to 11, inclusive, I have shown a plurality of yoke members for mounting different types of guns, one of these members being provided with a hinged clamp 92 connected with a lower clamping member 93 formed on portion 94 which is suitably apertured for receiving a pin or pins adapted to be passed through apertures 95 formed in ears 96 upstanding from the sides of the base. Another form of securing member comprises an upper clamping device 97 provided with a complementary clamping

member 98 carried by lower portion 99 suitably apertured and adapted to be engaged by a pin or pins as in the previous instance. A yoke member 100 pivoted at 5 101 passes around the barrel of the gun and aids in retaining the gun in position.

In connection with the foregoing I provide a two-part periscope for the purpose of observing the sights of the gun from a 10 point below the gun base. A lower periscope member includes a casing 104 with a mirror 105 therein, said casing being mounted upon an arm 106 and secured to said arm by means of suitable devices 107. 15 This arm has adjustable connection with an arm 108 rigidly connected with the vertical supporting frame as shown at 109. The adjustable connection of any suitable character is designated 110. The upper periscope member includes a casing 111 having a mirror 112 mounted therein, said casing being adjustable vertically within side members 114 mounted on a channel member 115 co-operating 20 with a member having a corresponding cross section designated 116, said member being secured to the base by means of bolts or rivets 117. Vertical slots 118 permit of the raising and lowering of casing 111 and thumb screws 119 serve to secure 25 the casing in its adjusted position. Additional thumb screws 120 provide for engagement between the adjustable channel member 115 and the complementary member 116 secured to the gun base. A trigger 30 pull is designated 124 and is pivoted at 125. Additional securing means for the gun are shown at 126 this device or devices being apertured for the purpose of receiving detachable pins or the like. A slot 128 35 shown in Fig. 3 is provided for the accommodation of the trigger pull 124.

The cartridge reel 84 carried by arm 85 may be secured to either the right or left side of the machine and to either upright 28 or 40 29, being detachable by means of thumb screws 87. The entire mechanism may readily be prepared for removal from one place to another in view of the manner of assembling the elements thereof. The base 45 10 is provided with integrally formed socket members 5 which accommodate the detachable legs 6 for supporting the device. Trunnions 27 are held in position by detachable pins 27' permitting the super- 50 structure to be removed from the base, and the housing for shaft 38 and all of the gearing directly connected therewith may be detached from the base at 7 and 7'. The journal boxes there shown have hinged 55 60 covers secured by thumb screws 7. In this operation, arms 32 carrying sleeves 35 and gears 36 are folded against uprights 28 and 29. The sections of the periscope are removable by the operator to enable him to 65 have freedom of action in high angle firing.

The mirrors of the periscope are mounted in slots in the sides of the casings 104 and 111 and are secured by engaging devices 105' and 112', being therefore readily detachable when it is necessary to insert new 70 mirrors.

While in the description of this mechanism I have referred to its use in connection with certain guns of the United States Army, it should be understood that in essential features the device is adapted for 75 all types of machine guns.

I claim:—

1. In a device of the class described, a supporting member, a rotatable member carried thereby, a frame having pivotal connection with the rotating member, a gun base having pivotal connection with the frame, and means for adjusting said gun base vertically and at an angle with the frame. 80

2. In a device of the class described, a supporting device, a rotatable member carried thereby, a frame having pivotal connection with the rotating member, a bracket mounted for vertical adjustment with reference to the frame, and a gun base mounted 90 for angular adjustment in a vertical plane with reference to said bracket.

3. In a device of the class described, a supporting device, a rotating member 95 mounted thereon, a frame comprising a plurality of spaced bars, said frame having pivotal connection with the rotating member, means for adjusting the angular relation of the frame to the rotating member, a gun base 100 extending between the spaced members of the frame, a guiding and supporting device mounted between said spaced members and means for adjustably connecting the device last-named with the gun base. 105

4. In a device of the class described, a supporting device, a rotating member mounted thereon, a series of teeth extending around the circumference of the supporting member, a threaded member co-operating 110 with said teeth, a pivoted bracket carrying the threaded member, and adapted to turn the latter into and out of engagement with the teeth, a frame having pivotal connection with the rotating member, adjusting means for controlling the angular position of the frame, a gun base extending through the frame and means for adjusting the angular position of the gun base with reference to the frame. 115

5. In a device of the class described, a supporting device, a rotating member mounted thereon, a supporting frame comprising a plurality of angle bars and a transverse member, said frame having pivotal 120 connection with the rotating member, a gun base mounted transversely of the frame, a device having pivotal connection with the gun base and means for guiding said device along the flanges of the angle bars. 125 130

6. In a device of the class described, a supporting device, a rotating member carried thereby, a frame pivotally mounted on the rotating member, said frame including 5 a plurality of spaced angle bars, the outer angles constituting the front portion of the frame, a gun base, and a vertically movable guiding device positioned between the angle bars and having adjustable connection with 10 the gun base permitting the inclination thereof in a vertical plane, said guiding means carrying devices engaging adjacent flanges of the respective angle bars.

7. In a device of the class described, a pivotally mounted frame, means for supporting and rotating said frame, a guiding device operating within the frame, a gun base including a plurality of flanged members provided with a curved slot, means for pivoting 15 the gun base to said guiding device, means passing through said slot for adjusting the gun base with reference to the guiding device, and means for controlling the vertical elevation of the guiding device with 20 reference to said frame.

8. In a device of the class described, a pivotally mounted frame, means for supporting the latter, means for controlling the angular position of the frame, a gun base movable 25 vertically with reference to the frame and movable at an angle with reference thereto, a two-part periscope, one section thereof having connection with the gun base and the other section with the lower portion of the 30 frame.

9. In a device of the class described, a pivotally mounted frame, means for rotating said frame on a vertical axis, means controlling the inclination of the frame, a gun base, 35 guiding means movable vertically within the frame, means for controlling said verti-

cal movement, a gun base having pivotal and adjustable connection with the guiding means, and a two-part periscope, one section of which has adjustable connection with 45 the gun base, the other section having adjustable connection with the lower portion of the frame.

10. In a device of the class described, a pivotally mounted frame, means for rotating 50 said frame with reference to its vertical axis, a gun base mounted for vertical movement with reference to the frame and for movement angularly in a vertical plane, securing means carried by the gun base, and 55 clamping devices for retaining said gun on the base and adapted for connection with said securing means.

11. In a device of the class described, a supporting device, a rotating member carried 60 thereby, a frame having pivotal connection with the rotating member, detachable and adjustable means for controlling the position of the pivoted frame, a bracket mounted for vertical adjustment with reference to the frame, and a gun base mounted 65 for angular adjustment in a vertical plane with reference to said bracket.

12. In a device of the class described, a supporting device, a rotating member carried 70 thereby, a frame having pivotal connection with the rotating member, means for controlling the position of the pivoted frame and including a threaded member and a removably mounted transverse shaft and 75 gearing for operating the threaded member, a bracket mounted for vertical adjustment with reference to the frame, and a gun base mounted for angular adjustment in a vertical plane with reference to said bracket. 80

In testimony whereof I affix my signature.
WILLSE LAWRENCE.
